BOTTLE CLOSURE

Stephen J. Kneapler, Miami, Fla., assignor to Richford Corporation, Farmingdale, N.Y., a corporation of New York

Filed Nov. 17, 1967, Ser. No. 9,459

Term of patent 14 years

U.S. Cl. D9—285
Int. Cl. D9—99FIG. 1

FIG. 2

FIG. 3

FIG. 4

FIG. 1 is a top front perspective view of a bottle closure embodying my design;

FIG. 2 is an elevational view thereof;

FIG. 3 is a top plan view thereof;

FIG. 4 is a bottom plan view thereof; and

FIG. 5 is a fragmentary section thereof along the line 5—5 in FIG. 2.

The dominant features of my new design are shown in solid lines in the drawing.

I claim:

The ornamental design for a bottle closure, substantially as shown and described.
